US00D917569S

(12) **United States Design Patent** (10) **Patent No.:** **US D917,569 S**
(45) **Date of Patent:** **** Apr. 27, 2021**

(54) **PORTABLE INFLATOR**

(71) Applicant: **VIS, LLC**, Travelers Rest, SC (US)

(72) Inventor: **Sage Youngblutt**, Greenville, SC (US)

(73) Assignee: **VIS, LLC**, Travelers Rest, SC (US)

(**) Term: **15 Years**

(21) Appl. No.: **29/680,672**

(22) Filed: **Feb. 19, 2019**

(51) **LOC (13) Cl.** **15-02**

(52) **U.S. Cl.**

USPC **D15/7**

(58) **Field of Classification Search**

USPC D15/7-9; D13/103, 107-109; D24/111; D14/196

(57) **CLAIM**

The ornamental design for a portable inflator, as shown and described.

DESCRIPTION

FIG. 1 is a front perspective view of the portable inflator as shown in FIG. 1;

FIG. 2 is a front view of the portable inflator as shown in FIG. 1;

FIG. 3 is a rear view of the portable inflator as shown in FIG. 1;

FIG. 4 is a right side view of the portable inflator as shown in FIG. 1;

FIG. 5 is a left side view of the portable inflator as shown in FIG. 1;

FIG. 6 is a top view of the portable inflator as shown in FIG. 1; and,

FIG. 7 is a bottom view of the portable inflator as shown in FIG. 1.

The broken lines in the drawings are for the purpose of illustrating portions of the portable inflator and form no part of the claimed design.

1 Claim, 7 Drawing Sheets
